UNITED STATES PATENT OFFICE.

SAMUEL B. SHELDON, OF DULUTH, MINNESOTA.

GAS-PRODUCER ARRANGEMENT.

1,350,473.

Specification of Letters Patent. Patented Aug. 24, 1920.

Application filed June 11, 1918. Serial No. 239,362.

To all whom it may concern:

Be it known that I, SAMUEL B. SHELDON, a citizen of the United States, residing at Duluth, in the county of St. Louis and State 5 of Minnesota, have invented certain new and useful Improvements in Gas-Producer Arrangements, of which the following is a specification.

This invention relates to gas producers.

10 One of the objects of this invention is to simplify and improve means for feeding and distributing fuel.

Another object is to maintain in an improved manner the top of the gas producer 15 and the parts mounted thereon in a cool condition.

Another object is to provide a gas producer having its parts so constructed and arranged as to coöperate with each other in a 20 manner to meet the requirements for successful commercial operation.

These and other objects are accomplished by means of the arrangement disclosed by the accompanying sheets of drawings in 25 which Figure 1 is a plan view of my gas producer;

Fig. 2 is a fragmentary vertical sectional view of the upper part of the same, and

Fig. 3 is a vertical sectional view of the 30 fuel feeding and distributing mechanism.

The various novel features of my invention will be apparent from the following description and drawings and will be particularly pointed out in the appended claims.

35 In view of the fact that my invention relates to mechanism mounted on the top of the gas producer, only the upper part of the gas producer is shown.

The main body portion 10 of the gas producer has at its upper end a channel portion 11 in which the vertical flange 12 of the rotating top 13 moves. The top 13 and the parts mounted thereon are all driven by an 40 electric motor 14 through suitable mechanism. The shaft of the motor 14 is provided with a pinion 15 which meshes with a gear 16 mounted on a shaft connected to suitable gearing within a gear housing 17. Extending outward from this housing is a shaft 17'

45 carrying a pinion 18, which meshes with and drives a relatively large gear 19 mounted upon a shaft 20 to the outer end of which is secured a traction wheel 21 bearing upon the stationary body portion 10 of the gas producer, whereby the top of the gas producer is rotated. Secured to the other end

of shaft 17' is an eccentric 22 operatively connected to a yoke member 23 secured to a shaft 24 upon which a walking beam 25 is mounted. By means of this eccentric drive 60 arrangement the opposite ends of the walking beam 25 are given an upward and downward movement in opposition to each other. Secured to each end of the walking beam 25 is a poker 26 which is arranged and operates in a manner fully described in my co-pending application, Serial No. 239,361, filed June 11, 1918, by means of which the fuel in the coking zone is maintained in a uniformly opened or porous condition. 65

70 Mounted upon the top 13 of the gas producer is a fuel hopper 39 which receives its supply of fuel through a chute 40, the upper end of which is in register with the supply opening 41 of a coal bin 42. As shown, the outlet 41 is arranged concentrically with respect to the gas producer and the fuel hopper 39 arranged eccentrically with respect thereto, the chute 40 accordingly being arranged at an angle. It will be appreciated, however, that these parts may be arranged in accordance with requirements. 75

80 The fuel hopper 39 preferably is divided into two compartments 43 and 44 by a central wall or partition 38 which is hollow for the purpose of cooling same by means of water or any other suitable cooling medium. Mounted within each of the compartments 43 and 44 for reciprocation therein is a plunger 46 operatively connected to an arm 90 47 keyed to a shaft 48 to which is connected an arm 49 connected in turn to a rod 50, one end of which is connected to a shaft 51 through an eccentric 52, whereby each of the plungers 46 is reciprocated. It will be 95 understood that each of the plungers has its own reciprocating mechanism, the latter in each case being operatively connected to the operating shaft 51, to one end of which is secured a gear 53 which is driven by gear 19. If it is desired to vary the stroke of either plunger 46 the same may be accomplished by connecting the free end of the corresponding rod 50 at different points along the arm 49. It will be appreciated, 100 however, that the stroke of the oppositely actuated plungers may be varied in different ways.

105 Fuel from the hopper 39 flows downwardly in front of the plungers 46, the fuel sloping off in front of said plungers at an angle of repose. The flow of fuel from the

hopper 39 is controlled in part by a plate 27 pivotally connected to a member 28 which may be raised or lowered by means of a gear 29 in mesh with a rack 30 carried by 6 the member 28. The plate 27 normally is maintained in its lower or vertical position by a weight 31 and carried by an arm 31' in turn carried by said plate 27.

The fuel in front of the oppositely actuated plungers 46 is pushed onto a distributer 54 which is eccentrically arranged with respect to the vertical center of the gas producer and which is rotated from the shaft 51 by a belt or chain 55 passing around a 15 pulley 56 on said shaft, around intermediate idler pulleys 57 and 58 and around a pulley 59 mounted at the upper end of the distributer 54. This distributer 54 is hollow for the purpose of water cooling, the 20 water being fed down through the distributer by a pipe 60 and overflowing at 61 to form a water seal in the annular channel member 62. The floor 63 of the hopper 39 is water cooled in addition to the partition 25 or wall 38 between the compartments 43 and 44.

The top 13 of the gas producer is cooled by forcing water into a central chamber formed by an annular wall 64 having 30 circumferentially arranged openings 65 through which the water may flow radially outwardly over the upper surface of the top for cooling the latter. The excess amount of cooling water supplied in this way may 35 overflow the sides of the producer.

It is evident that there may be various modifications of the invention as herein particularly shown and described and it is my intention to cover all such modifications 40 which do not involve a departure from the spirit and scope of the invention as set forth in the following claims.

I claim:

1. In a gas producer, the combination of 45 a fuel hopper having a water jacketed floor

directly above the top cover of the producer and so closely located to the top cover as to necessitate artificial cooling to prevent warping, a fuel distributer mounted adjacent to said hopper floor, means for cooling 50 said distributer, the fuel hopper floor extending and terminating directly over the distributer, a plunger for feeding fuel from the hopper onto said distributer, and means for actuating said plunger and distributer. 55

2. In a gas producer, the combination of a fuel hopper having a water jacketed floor directly above the top cover of the producer and so closely located to the top cover as to necessitate artificial cooling to prevent 60 warping, a fuel distributer mounted adjacent to said hopper floor, means for cooling said distributer, the fuel hopper floor extending and terminating directly over the distributer, a plurality of simultaneously 65 oppositely driven plungers to continuously supply fuel from the hopper onto said distributer, and means for actuating said plungers and distributer.

3. In a gas producer, the combination of 70 a top, and a fuel feed hopper mounted thereon and having a plurality of feed plunger chambers separated by a water cooled hollow partition, and water cooling means by which parts of the hopper may be maintained in a cool condition. 75

4. In a gas producer, the combination of a top, and a fuel feed hopper mounted thereon and having a plurality of fuel feed plunger compartments formed therein arranged 80 side by side and having the floor and partition between said compartments hollow for the reception of a cooling medium.

Signed at Duluth, Minnesota, this 3rd day of June, 1918.

SAMUEL B. SHELDON.
